ABSTRACT: A tool for bending metal straps such as those used to support service pipes and conduits intermediate a floor structure and ceiling suspended therebelow of the type separating successive floors in modern multiple-story commercial buildings. The strap-bending tool includes a pair of handles supported for relative pivotal movement between open and closed positions. One such handle is equipped with a strap holder adapted to have a strap inserted thereinto so as to extend downwardly along the holder-equipped handle. Pivotedly supported by such one handle below the holder thereon is a strap-bending element which underlies the free end portion of any strap inserted into the holder. A force applicator carried by the other handle is engageable with the strap-bending element to displace the same angularly when the handles are closed and thereby bend the free end portion of such strap about the anvil defined the lower edge of the strap holder.

STRAP-BENDING TOOL

DISCLOSURE

This invention relates to a tool for bending metal straps and the like and, more particularly, to a strap-bending tool especially suited for use in bending the elongated straps used as handers to support service pipes and conduits in the space provided between each floor structure and the ceiling suspended therebelow which separate the successive floor levels of a multiple-story commercial building.

In the construction of modern multiple-story office buildings and similar commercial structures it is common to provide for each floor level or story a ceiling that underlies the divider or floor structure thereabove and is suspended at a distance therebelow sufficient to provide a relatively large intermediate space that accommodates service pipes and conduits of various types such as telephone lines and electric conduits, water pipes, heating and ventilating conduits, etc. Such pipes and conduits are necessarily supported from the floor structure that they underlie, and in this same reference, the ceiling which conceals such pipes and conduits also must be supported by the overlying floor structure. To provide such support, it is quite common for each floor structure to be equipped with a plurality of hangers or straps that extend downwardly therefrom and are secured thereto in any convenient manner, as for example, by being attached to the beams, joists, webs or other components of the floor structure by suitable fasteners or other appropriate means; and the various pipes, conduits and other components are affixed to these straps. For this purpose, it is usual for the workmen to bend each strap at the elevation suitable for securing a service component thereto.

In the past, such straps have been bent by workmen with any tool that he may have convenient, usually a pair of pliers. Bending the straps in this manner is not satisfactory because it is physically difficult (the straps being quite sturdy), and when the strap is to be bent a considerable distance from the free end thereof much of the mechanical advantage usually gained from the relatively long handles of the pliers is lost, thereby making the bending operation even more difficult and often resulting in a bend or turn in the strap that is irregular. In view of the foregoing an object, among others, of the present invention is to provide an improved tool for bending metal straps and the like.

Another object of the invention is that of providing a strap-bending tool of the character described that enables a strap to be quickly and easily gripped or held by the tool preparatory to the bending operation, and that also enables a bent strap to be quickly and easily separated from the tool subsequent to the bending operation.

Another object of the invention is in the provision of an improved strap-bending tool which applies a uniformly distributed bending force to a strap across the entire width thereof, and which tool is able to accommodate straps of various widths without loss of such uniformity in force distribution.

A further object of the invention is to provide a tool of the character described having a pair of elongated handles pivotally moveable with respect to each other and one of which is equipped with both a strap holder and a strap-bending element disposed therebelow and the other of which is equipped with a force applicator engageable with the bending element so as to displace the same into engagement with a free end portion of a strap held by the tool and then bend such end portion along a relative straight line at a predetermined location defined by an anvil edge provided by the strap holder.

Additional objects and advantages of the invention, especially as concerns particular features and characteristics thereof, will become apparent as the specification develops.

An embodiment of the invention is illustrated in the accompanying drawing in which:

FIG. 1 is a broken perspective view of a typical floor structure and suspended ceiling showing elongated metal straps arranged therewith of the type with which the bending tool is especially useful;

- 5 FIG. 2 is a front view in elevation of the bending tool;
  - FIG. 3 is a side view in elevation of the tool in open position and showing an associated strap in phantom lines;
  - FIG. 4 is a side view in elevation similar to that of FIG. 3 but illustrating the tool in the closed position thereof;
  - 10 FIG. 5 is a top plan view of the tool taken along the line 5—5 of FIG. 4; and
  - FIG. 6 is a broken front view in elevation of the tool in the closed position thereof, the view being taken along the line 6—6 of FIG. 4.
  - 15 As indicated hereinbefore, strap-bending tools embodying the present invention are useful in bending elongated metal straps such as those provided in association with floor-ceiling structures of multiple story office buildings for supporting various service components including pipes, heating and cooling conduits, electric and telephone conductors, and often a suspended ceiling spaced below the overlying floor structure so as to conceal the service components interposed therebetween. Illustrative straps of this type are shown in FIG. 1 in association with a typical floor structure and suspended ceiling, and which floor structure in the case of commercial buildings maybe of prestressed concrete composition and include a horizontal floor or flange component 10 formed integrally with a plurality of spaced-apart joists or beams or web components 11 depending therefrom.
  - 20 A plurality of metal straps 12, usually formed of steel, are secured to the ceiling structure in any suitable manner as by being pinned to the depending joists 11 as shown.
  - 25 The straps 12 project downwardly for a considerable distance below the joists 11 and have free end portions 14 that are bent laterally at an appropriate location so as to support a component thereon as, for example, the ceiling component 15 shown by broken lines. The location at which the end portion 14 is bent or turned laterally depends upon the particular component to be supported by the strap. In the case of service conduits to be supported thereby, the bend will occur at an elevation much closer to the floor structure or joists 11 thereof so that such conduits are interposed between the floor structure and the ceiling 15 suspended therebelow.
  - 30 The strap-bending tool illustrated in FIGS. 2 through 6 is denoted in its entirety with the numeral 16 and, as shown in most clearly in FIG. 3, it comprises a pair of elongated, longitudinally extending handles 17 and 18 of U-shaped configuration in cross section (the handle 18 being arcuate to make it easier to grip) and supported for pivotal movement relative to each other between the open position shown in FIG. 3 and the closed position illustrated in FIG. 4. As respects such pivotal movement of the handles 17 and 18, the handle 17 is equipped adjacent the upper end thereof with an essentially L-shaped bracket 19 that may be welded or otherwise rigidly secured thereto. The handle 18 is located along the inner surface of the base leg of the bracket 19 and is pivotally carried thereby through a pivot pin 20 that extends through the handle 18 and bracket 19 as is most evident in FIGS. 2 and 5. Clearly, then,

  - 55
  - 60
  - 65
  - 70
  - 75
- The tool 16 also includes a strap holder or guide 21 having a generally L-shaped form, as seen in FIG. 5. In this respect, the holder 21 has a leg 22 fixedly related to the handle 17 and the aforementioned pin 20 extends through the leg 22, as shown best in FIG. 5. The holder 21 has an additional leg 24 oriented in a generally normal disposition relative to the leg 22 and it extends along the stem or branch 25 of the L-shaped bracket 19 in space parallel relation therewith so as to define a strap-receiving opening 26 therebetween. The space 26 is enclosed on three sides by the legs 22 and 24 of the strap holder 21 and base 25 of the bracket 19, and it is sufficiently large to enable a strap 22 to be inserted thereinto as shown in both FIGS. 3 and 4.

Adjustable displacements of the tool 16 in longitudinal directions relative to a strap 12 seated within the opening 26 can be effective so as to accurately locate the tool with respect to the line along which the free end portion 14 of the strap is to be bent. In this connection, it may be observed that the strap holder 21 is provided with a lower edge 27 defining an anvil along which an end portion of any such strap 12 can be bent, as shown in FIG. 4.

The tool 16 further includes a strap-bending element or platform 28 which straddles the handle 18 and is of U-shaped construction having spaced legs 29 and 30 respectively disposed on opposite sides of the handle 18 and pivotally carried thereby through a pin 31 extending through the handle 18 and element 28, as is most evident in FIGS. 2 and 6. The strap-bending element 28 is freely pivotal or swingable with respect to the handle 17 between the open position shown in FIG. 3 in which the element 28 extends downwardly therewith and the closed position shown in FIG. 4 in which the element 28 has been displaced through a distance of approximately 90 degrees in a clockwise direction to turn or bend the end portion 14 of the strap 12 laterally.

The handle 18 is equipped therewith with a projection or force applicator 32 that may be welded or otherwise fixedly secured thereto. The force applicator 32 disposed adjacent the strap-bending element 28 and is in substantial alignment therewith when the tool is in its open position, as shown in FIG. 3. The handle 17, in substantial alignment with the applicator 32, is provided with a slot or opening 34 through which the applicator 32 projects as the handle 18 is displaced toward the closed position thereof. Such displacement of the handle causes the force applicator 32 to engage the strap-bending element 28 and displace it from the open position thereof shown in FIG. 3 into the closed position illustrated in FIGS. 4, 5 and 6. It will be noted that the force applicator 32 tapers somewhat to a reduced dimension adjacent its free end and has an angular inclination relative to the plane of the handle 18 so as to swing forwardly and upwardly as the handle 18 is closed to enable the applicator to remain in force-applying engagement with the bending element 28 and thereby cause the same to turn or bend the end portion 14 of the strap 12 into the lateral disposition shown in FIG. 4.

In use of the strap-bending tool 16, a strap to be bent (a strap 12 depending from a joist 11, for example, although any other strap or generally planar component of similar properties can be bent) is inserted into the opening 26 so that the anvil or lower edge 27 of the strap holder 21 is positioned along the strap at the location at which it is to be bent. Insertion of the strap is most easily accomplished by transverse displacement thereof relative to the tool 16 through the open side of the strap holder 21, and should any slight adjustment between the strap and tool be required they can be moved longitudinally relative to each other to effect the desired positioning. The strap will then have the general disposition shown in FIG. 3 in which the lower end portion thereof extends downwardly along the handle 17 in overlying relation with the strap-bending element 28.

The handles 17 and 18 are then displaced angularly relative to each other which most usually defines the condition in which the handle 18 is pivoted in a clockwise direction, as viewed in FIG. 3, into the closed position shown in FIG. 4 while the handle 17 is maintained in general longitudinal alignment with the strap 12. However, it should be recognized that the handle 17 might be displaced angularly in either a clockwise or counterclockwise direction as viewed in FIG. 3 so as to bend the strap 12 along the upper edge of the leg 24 of the strap holder 21. Such angular displacement of the handle 18 relative to the handle 17 causes the force applicator 32 to move through the opening 34 and into engagement with the strap-bending element 28 and displace the same in a clockwise direction from the open position illustrated in FIG. 3 into the closed position shown in FIG. 4. It is evident that such movement of the strap-bending element 28 causes the lower end portion 14 of the strap 12 to be bent or turned laterally so as to have a substantially normal orientation relative to the major length or plane of the strap 12, as seen in FIG. 1 and 4.

The substantial width of the strap-bending element 28 assures a substantially uniform application of force across the entire width of strap 12 during bending thereof and it also enables the tool 16 to accommodate straps of lesser width than that of the holder 21 and bending element 28 while still providing such uniform force distribution. Irrespective of its width, any bent strap can be removed from the strap holder 21 by transverse displacement thereof relative to the tool so as to withdraw the strap through the open side of the holder 21. It will be appreciated that such removal of a strap of the tool is accomplished after the handles 17 and 18 have been displaced slightly so as to relieve the force otherwise applied to the strap-bending element 28 by the force applicator 32.

While in the foregoing specification an embodiment of the invention has been described in considerable detail for purposes of making a complete disclosure thereof, it will be apparent to those skilled in the art of numerous changes may be made in such details without departing from the spirit and principles of the invention.

What is claimed is:

1. A tool for bending metal straps and the like, comprising a pair of longitudinally extending handles supported for pivotal movement relative to each other between open and closed positions, a strap holder carried by one of said handles for confining a portion of any such strap against lateral displacements with respect thereto and providing an anvil along which an end portion of such strap can be bent, a strap-bending element supported by said one handle for movement between open and closed positions and being engageable with such strap in moving into its closed position to bend the same laterally about said anvil, and a force applicator carried by the other of said handles and being engageable with said strap-bending element upon movement of said handles into their closed position to displace said strap-bending element into its closed position and thereby bend any such strap confined by said strap holder.
2. The tool of claim 1 in which said strap holder movably confines any such strap and accommodates adjustable displacements of said tool relative thereto in longitudinal directions for selectively locating such strap with respect to the aforesaid anvil provided by said strap holder and along which the strap is to be bent.
3. The tool of claim 2 in which said strap holder is open along one transverse edge thereof so as to accommodate entrance and removal of a strap.
4. The tool of claim 1 in which said strap-bending element spans the aforesaid one handle transversely and has approximately the same transverse width as said strap holder and pivotally supported by said one handle for free-angular displacements with respect thereto.
5. The tool of claim 4 in which said one handle is provided with an opening therein adjacent said strap-bending element for passing said force applicator therethrough to enable the same to engage said strap-bending element and displace the same into the closed position thereof.
6. The tool of claim 1 in which said strap holder movably confines and such strap and accommodates adjustable displacements of said tool relative thereto in longitudinal directions for selectively locating such strap with respect to the aforesaid anvil provided by said strap holder and along which the strap is to be bent, and in which said strap-bending element spans the aforesaid one handle transversely and has approximately the same transverse width as said strap holder and pivotally supported by said one handle for free angular displacements with respect thereto.
7. The tool of claim 6 in which said one handle is provided with an opening therein adjacent said strap-bending element for passing said force applicator therethrough to enable the same to engage said strap-bending element and displace the same into the closed position thereof.
8. The tool of claim 7 in which said strap holder is open along one transverse edge thereof so as to accommodate entrance and removal of a strap.

9. The tool of claim 8 in which the aforesaid one handle is equipped adjacent an end thereof with a generally L-shaped bracket and the other of said handles is pivotally secured to said bracket, and in which said strap holder is an L-shaped

component secured to said bracket and having a leg spaced from the base thereof to define a space therebetween within which any such strap is confined by said strap holder.
